MACHINE FOR TURNING OR THREADING BOLT BLANKS AND THE LIKE

Application filed June 27, 1923. Serial No. 647,969.

My invention aims to provide a machine for turning or threading and at the same time producing a profiled product; that is, one which is not of the same size throughout its length.

The accompanying drawings illustrate a machine embodying the invention, in which Fig. 1 is a front elevation;

Fig. 2 is a vertical cross-section, showing 10 parts in elevation;

Fig. 3 is a side elevation partly in section showing a profile bar;

Fig. 4 is a plan, partly broken away, of 15 the cutter head and related parts;

Fig. 5 is a front elevation of the same parts;

Fig. 6 is a similar view showing a different position of the mechanism;

Fig. 7 is an elevation of a bolt produced 20 in the machine.

The invention is applicable to various types of machine. I have shown it applied to a single unit of a known style of multiple vertical machines which is used for making stay-bolts and the like. This machine has a base 1 with uprights 2 and 3 and a cross-head 4. A blank 5 is supported at its lower end in a socket 6 which is rotated by suitable gearing so as to turn the blank. A cutter-head indicated as a whole at 7 surrounds the blank and has its cutter engaging the same and travels downward along the blank, so as to turn the latter as it is rotated. The upper end of the blank is held by a centering device 8. The cutter-head is carried at the lower ends of rods 9 which pass freely through ears of the centering device 8 and which at their upper ends are attached to a nut 10 on a threaded shaft 11 which is supported in bearings at its lower end and rotated by means of gearing in a box 12. Also the nut 10 together with the supporting rods and cutter-head are suspended from straps 13 which pass over friction pulleys 14 and carry counterweights 15 at their ends. The nut 10 is engaged with the screw shaft 11 when the cutter-head is to be fed downward. When it is to be lifted the nut, which is a divided nut, is disengaged from the shaft 11, and the rotating friction pulleys 14 lift the cutter-head rapidly to the

top of its travel, at the same time lifting the centering head 8 and freeing the blank.

The cutter-head comprises a casing portion 16, Figs. 4 and 5, with lateral arms 17 and 18 having elongated slides 19 and 20 at 55 their ends which fit in guides in the columns 2 and 3 of the machine. The cutters 21 are mounted in blocks 22 which are carried by pivot-pins 23 mounted in the top of the casing and which are connected by toggle links 60 24 to a part which is rotatably supported in the casing of the head. The part which is rotatable comprises two rings. The ring 40 projects upward within the ring 25 as indicated in Fig. 4 and carries directly the pivoted 65 outer ends of the toggle links. The ring 25 is angularly adjustable on the ring 40 as hereinafter explained. When the ring 25 is turned to the right (clockwise in Fig. 4) the ring 40 moves similarly and the cutters are moved inward to turn the blank to a smaller diameter, and when the ring is turned in the opposite direction the cutters are farther separated. A spring 26 tends to turn the 70 ring 25 in the direction to open the cutters. 75

The ring is turned more or less in the closed direction by means of a profile bar shown in Fig. 3 consisting of a supporting member 27 on the face of which is detachably fastened a profile member 28, the contour of which is such as to produce the desired opening and closing of the cutters to turn the blank to the desired diameters at successive points in its length; the face of the profile bar bears on a tumbler 29 on a pin 30 which projects from the side of the ring 25. 80 85

The profile bar is suspended by a pin 31, Fig. 3, from the cross-head 4 of the machine and is located so that the back of it bears 90 against a shoulder 32 on a fixed part of the head, the lateral extension 18. By locating the profile bar in this way between the relatively movable parts of the head, a very accurate control of the cutters is secured. If the head moves laterally in its vertical guides, the profile bar moves with it because of the loose support of the bar at its upper end. Consequently any such lateral movement of 95 100

the head has no effect on the adjustment of the cutters or on the profile of the work.

The tumbler 29 is for the purpose of permitting a return movement of the carrier without closing the cutters on the work. On the downward movement, as shown in Fig. 5, it bears against the profile bar which forces the cutters in as explained above. On the upward movement, Fig. 6, it is tilted in the manner shown and the spring is allowed to hold the cutters wide open, pressing the tilted tumbler against the profile bar. To prevent tilting on the downward movement the tumbler has a tail 33 which bears on a stop-pin 34 carried by a bracket 35 which is fastened on the projection 36 at the side of the ring 25; which projection also carries the pivot pin 30 of the tumbler.

The head is provided also with a hand adjustment for setting the two rings of the movable part with relation to each other. The ring 25 is carried in adjustable relation with the ring 40 which projects upward within the ring 25 and carries the pivots 41 of the toggles as shown in Fig. 4. The ring 25, in any position in which it is held by the profile bar, serves as an abutment in relation with the ring 40 to adjust the tools inward or outward. The adjusting means shown is of a common type consisting of a scale 42 carried by the part 25 against which slides a block 43 pivotally mounted on a stud 44 at the side of the ring 40. The scale 42 carries at its left-hand end a nut 45 pivoted on a vertical axis, through which is screwed a screw 46 passing through the block 43, engaging the latter by shoulders at opposite sides so as to prevent longitudinal movement therein, and free to be turned therein by means of the head 47. A set screw 48 serves to clamp the screw 46 in the nut 45. Thus the two rings 25 and 40 are fixed in any desired relative adjustment, the ring 25 being fixed by the bearing of the tumbler 29 against the profile bar. The screw 46 may be turned to provide a greater or less opening of the cutters. This adjustment therefore is an absolute one which determines the initial diameter of the work and which is supplemented by the action of the profile bar in determining the taper of the work.

The cutter head is very accurately controlled as I have described above; and the addition of a centering device 8 at the upper end, co-operating with the centering socket at the lower end, by holding the blank accurately assists in securing an accurately turned product. The centering device is illustrated only in outline. It may be of any one of various known types. The design illustrated comprises a vertically movable carriage guided by the uprights 2 and 3. This carriage supports the dead center 8^a and is preferably provided with means (not shown) by which it can be rigidly clamped to the fixed uprights. At the beginning of the operation the head 7 is

lifted, and when it reaches the carriage of the centering device it carries the same up if the clamping means thereof have been previously released, it being remembered that the suspension rods 9 pass freely through the ears of the carriage. A blank is inserted with its polygonal head in the socket 6. The cutter-head 7 is then lowered to a position which aligns the tools thereof with the end of the work. At the same time the carriage 8 follows downward and the point or dead center 8^a engages a conical recess formed in the end of the blank and the carriage is then clamped to the uprights. Thus the work is accurately centered for the turning or threading operation, which in turn is accurately controlled by the absolute adjustment of the cutters and by the taper of the controlling profile bar.

The cutters referred to may be either turning cutters for rounding the blank or they may be chasers or threading cutters for forming the threads on the bolt. Or the cutter-head may carry both turning cutters and chasers as has been done in some machines. Fig. 7 indicates a product of the machine, using turning cutters. This is a blank with a head 37 and a tapering shank 38, the end 39 of which is beveled. The product of the machine may be either such a blank turned to approximate size and shape and ready to be threaded in another machine, or may be a finished, threaded bolt. And the profile bar may be shaped to produce a continuous taper as illustrated or to produce various other profiles.

Though I have described with great particularity of detail a certain embodiment of my invention yet it is not to be understood therefrom that the invention is restricted to the particular embodiment described. Various modifications in detail and in the arrangement of the parts may be made by those skilled in the art without departing from the invention as defined in the following claims.

What I claim is:—

1. A machine for cutting bolt blanks including in combination a cutter-head carrying a plurality of cutters embracing the work, said cutters being swingable in an arc, a tapered profile bar suspended from a pivot situated beyond the highest point of travel of the cutter-head, a portion of said profile bar being situated between two parts of the head and adapted to cause a separation or approach of said parts so as to swing the cutters toward or from the work.

2. The combination with a cutter-head having two parts one turning on the other and a loosely pivoted profile bar for controlling such relative movement, and means secured to one part of said cutter-head arranged to co-operate with said profile bar during the cutting movement of the cutter-head and arranged to move to inoperative position during opposite movement of the cutter-head.

3. The combination with a cutter-head including two parts one rotatably mounted on the other cutters swingable in an arc arranged to be moved toward and from the work in response to relative movement between two parts of the cutter-head so as to vary the size of the work cut, a vertically extending profile bar floatingly pivoted above the cutter-head, and means for controlling the relative movement of the two parts of the cutter-head including a tumbler which is operative to cause an advance of the cutters toward the work during cutting movement of the head and is automatically rendered inoperative during a retracting movement of the cutter-head.

4. The combination with a cutter-head having vertical movement and comprising two parts one arranged to turn with respect to the other, cutters swingable in an arc carried by said head and adapted by such turning movement to vary the size of the work cut and a profile bar pivotally suspended independently of the head acting against one of the parts thereof and reacting against the other so as to control such relative movement and means for manually adjusting the relation of said parts to each other.

In witness whereof, I have hereunto signed
30 my name.

JULIUS KINDERVATER.
